UNITED STATES PATENT OFFICE.

ACHILLES DE KHOTINSKY, OF CHICAGO, ILLINOIS, ASSIGNOR TO CENTRAL SCIENTIFIC COMPANY, OF CHICAGO, ILLINOIS, A CORPORATION OF ILLINOIS

TERMOREGULATOR.

1,227,760.

Specification of Letters Patent. Patented May 29, 1917.

Application filed April 29, 1916. Serial No. 94,511.

To all whom it may concern:

Be it known that I, ACHILLES DE KHOTINSKY, a citizen of the United States, residing at Chicago, in the county of Cook and 5 State of Illinois, have invented certain new and useful Improvements in Thermoregulators, of which the following is a specification.

This invention relates to a thermally controlled circuit-closing device and has for its 10 principal object the provision of a thermoregulator of the type in which a circuit is closed by the expansion of a liquid contained therein and forming one terminal of the circuit, arranged to respond to slight variations 15 in temperature and to be readily and accurately adjusted to close the circuit at different temperatures.

A further object of my invention is the 20 provision of a thermoregulator of the above described type in which the condition of the contacts is readily observable without dismantling the device.

Further objects and advantages of my invention will be apparent as it is better understood by reference to the following specification when read in connection with the accompanying drawing, illustrating the preferred embodiment thereof, in which the 25 figure is a vertical longitudinal section 30 through the thermoregulator.

Referring to the drawing, 1 indicates a tube which in practice is filled with a conducting fluid such as mercury which expands 35 and contracts under varying thermal conditions. The closed end of the tube 1 is adapted to be disposed at the point at which the temperature is to be observed, as for example in a water bath (not shown), and is 40 broken in the illustration for the reason that the end may assume varying forms, depending upon the particular purpose to which it is applied. Threadedly mounted upon the end of the tube 1 is a coupling 2 in the upper 45 end of which a member 3 is threadedly secured. The member 3 is interiorly tapered at 4 to receive the glass tube 5 having a capillary bore 6, the tube 5 being tapered to correspond to the tapered opening 4 and 50 adapted to fit snugly therein. The member 3 is provided with a knurled head 7 whereby it may be adjusted with respect to the tube 1 to vary the normal height of the mercury which rises in the capillary bore 6, whereby 55 the temperature at which the circuit is closed

may be varied. A set screw 8, threadedly mounted in the coupling 2, may be employed to lock the member 3 in its adjusted position. The upper end of the glass tube 5 is tapered and fits snugly within the correspondingly 60 tapered opening in a tube 9 to the upper end of which the cap 10 is threadedly attached. A screw 11 having a knurled head 12 is disposed through the cap 10 and is provided at its lower extremity with a contact 13, 65 preferably of platinum, extending into the bore 6 in the glass tube 5. By operating the screw 11 a finer adjustment of the contact 13 with respect to the mercury in the bore 6 is possible. A knurled lock nut 14 is disposed 70 upon the screw 11 and serves to lock it in adjusted position.

The mode of operation of the thermoregulator will be readily understood by the 75 following brief description: The member 3 is separated from the coupling 2 and the tube 1 is filled with mercury up to within substantially ten millimeters of the top of the coupling 2. The member 3 is replaced and the knurled head 7 is turned until the 80 underside thereof is within substantially one millimeter of the top of the coupling 2. The cap 10 is then removed and all mercury above the glass tube 5 is removed after which the cap 10 is replaced and the knurled head 7 85 is manipulated to bring the meniscus of the mercury column in contact with the platinum contact 13. The coarser adjustment is made by means of the knurled head 7 and the finer by means of the knurled head 12. 90 The device is then ready for operation and may, of course, be adjusted to close the contact between the mercury column and the platinum contact 13 at any desired temperature. 95

As is well-known, sparking between the mercury and the metallic contact rapidly oxidizes the mercury with the resulting formation of a film of oxid and devices of this character have been heretofore unreliable because it has been impossible to determine whether or not a film of oxid had formed without dismantling the device. Inasmuch as this involved considerable trouble it has frequently been overlooked with the result 100 that the device failed at critical periods. By employing the glass tube 5 it is possible to readily see the condition of the mercury within the bore 6 at all times so that a mere glance is sufficient to warn the person in 110

charge that the bore requires cleaning. This is accomplished by separating the member 3 from the connector 2 and the cap 10 and passing a ball of absorbent cotton through 5 the bore 6.

It will be appreciated from the foregoing that I have perfected a thermoregulator of simple construction which may be quickly regulated to close a circuit at desired 10 temperatures and which overcomes a difficulty which has been experienced in the use of devices of this character so that my thermoregulator is more reliable and efficient than any heretofore known.

15 It will be apparent that various changes may be made in the form, construction and arrangement of the parts without departing from the spirit and scope of the invention or sacrificing any of its material advantages, 20 the form hereinbefore described being merely a preferred embodiment thereof.

I claim:

i. A thermoregulator comprising a tube 25 adapted to support a thermo-sensitive current-conducting fluid, a member adjustable relatively to said tube and provided with a tapered opening, a second member provided with a tapered opening and spaced from said first member, a glass tube having tapered 30 ends fitting snugly in said tapered openings and a relatively small bore, and a contact member supported by said second member and extending into said bore.

2. A thermoregulator comprising a tube 25 adapted to support a thermo-sensitive current-conducting fluid, a member adjustable relatively to said tube and provided with a

tapered opening, means for locking said member in adjusted position, a second member provided with a tapered opening and 40 spaced from said first member, a glass tube having tapered ends fitting snugly in said tapered openings and a relatively small bore, and a contact member supported by said second member and extending into said bore. 45

3. A thermoregulator comprising a tube adapted to support a thermo-sensitive current-conducting fluid, a member adjustable relatively to said tube and provided with a tapered opening, a second member provided 50 with a tapered opening and spaced from said first member, a glass tube having tapered ends fitting snugly in said tapered openings and a relatively small bore, and an adjustable contact member supported by said second member and extending into said bore. 55

4. A thermoregulator comprising a tube adapted to support a thermo-sensitive current-conducting fluid, a member adjustable relatively to said tube and provided with a 60 tapered opening, a second member provided with a tapered opening and spaced from said first member, a glass tube having tapered ends fitting snugly in said tapered openings and a relatively small bore, an adjustable contact member supported by said second member and extending into said bore, 65 and means for locking said contact member in adjusted position.

ACHILLES DE KHOTINSKY.
